(21) Appl. No.: **29/118,091**

CLAIM

(22) Filed: **Feb. 3, 2000**

The ornamental design for a shoe protector for use while
driving a motorcycle, as shown and described.

(51) LOC (7) Cl. **02-04**

DESCRIPTION

(52) U.S. Cl. **D2/913**

FIG. 1 is a front perspective view of a shoe protector for use
while driving a motorcycle embodying my new design;
FIG. 2 is a top plan view thereof;
FIG. 3 is a side plan view thereof; and,
FIG. 4 is a bottom plan view.

(58) Field of Search D2/913, 909, 960,
D2/949; D24/189, 190, 192; 36/77 R, 72 R,
7.2, 7.1 R, 77 M, 72 A, 72 B, 73

The broken lines in the Figures are for illustrative purposes
only and form no part of the claimed design.

(56) **References Cited**

The surfaces that are not shown in the Figures or described
in the specification form no part of the claimed design.
